BUFFING WHEEL

John F. Leslie, Mishawaka, Ind.

Original application October 26, 1949, Serial No. 123,738, now Patent No. 2,607,171, dated August 19, 1952. Divided and this application January 21, 1952, Serial No. 267,356

5 Claims. (Cl. 51—193)

1

This invention relates to improvements in buffing wheels, and more particularly to the type of buffing wheel as illustrated in my Patent No. 2,460,588, dated February 1, 1949, wherein a plurality of segments formed of fabric or the like are detachably anchored at the margin of a metal disc to form the buffing portion of the buff wheel and to be readily replaced with a minimum waste incident to replacement. This application is a division of my co-pending application, Serial No. 123,738, filed October 26, 1949, now Patent No. 2,607,171, issued August 19, 1952.

Prior buffing wheels of the type having cloth segments detachably connected to a metal or other rigid center member have been subject to various disadvantages. Among these disadvantages are the lack of uniformity of distribution of the cloth in each segment throughout its thickness, that is, the cloth segments are provided at a central portion thereof with securing means and are folded relative to that securing means to form a skirt whose edge defines a portion of the periphery of the buffing wheel. Since the segments have this skirt form, their centers are hollow and there is a lack of solidity and firmness crosswise of the segments.

Another disadvantage of such prior devices is the fact that they are difficult to assemble. The individual character of the segments and the tendency of those segments, while stationary and being assembled, to move one relative to the other, especially if hooked to a center support, presents some problems and requires the exercise of care and the expenditure of a greater amount of time to assemble the buff wheel than is desirable.

It is the primary object of this invention to provide a buff of the type utilizing peripheral segments detachably anchored to a rigid center member which overcomes the disadvantages mentioned above.

A further object is to provide a novel member for supporting the fabric body of a buff segment in desired form and for detachably anchoring the segment to the center member of a buff.

A further object is to provide a buff segment of folded skirt-like construction, which is substantially of uniform density throughout all cross-sections, and particularly to provide a buff segment of this character with novel means for mounting a filler insert therein.

2

A further object of the invention is to provide a novel positioning means for holding individual buff segments in desired position in skirted form and characterized by shoulders for draping the skirt, a restricted neck for anchoring the skirt, and a projecting apertured head for engagement with an attachment hook.

Other objects will be apparent from the following specification.

In the drawing:

Fig. 1 is a face view of a buffing wheel embodying my invention, with parts thereof broken away.

Fig. 2 is a transverse sectional view taken on line 2—2 of Fig. 1.

Fig. 3 is a face view of one of the buff segments.

Fig. 4 is an enlarged fragmentary detail sectional view of a buff segment taken on line 4—4 of Fig. 3.

Fig. 5 is a fragmentary face view of a modified form of center plate.

Fig. 6 is a fragmentary detail sectional view taken on line 6—6 of Fig. 5.

Fig. 7 is a fragmentary detail sectional view taken on line 7—7 of Fig. 5.

Fig. 8 is a view of a portion of the edge of the center plate illustrated in Fig. 5.

Fig. 9 is an enlarged perspective view of a buff foundation member.

Fig. 10 is a sectional view taken on line 10—10 of Fig. 9, illustrating the manner in which the fabric of the buff is carried by the member illustrated in Fig. 9.

Fig. 11 is a view of a modified embodiment of a buff segment, said view being taken with parts broken away.

Fig. 12 is a schematic illustration of the manner in which the buff segment shown in Fig. 10 is folded.

Referring to the drawings, and particularly to the embodiment of the invention illustrated in Figs. 1 to 4, the numeral 10 designates a center plate which is provided with integral hook members 12 which engage the eye portions 14 carried centrally by a plurality of adjacent skirt-type fabric buffering segments 16.

The plate 10 is preferably formed of metal but may be formed of plastic, wood or any other suitable material characterized by rigidity and strength. The plate has a central aperture 18 adapted to receive and fit around the arbor

(not shown) of a conventional buff device. In this connection it will be understood that the buffing wheel commonly comprises a plurality of units or assemblies of the character illustrated in Figs. 1 and 2 which are positioned side by side upon the arbor so as to provide an overall or composite buffing wheel of desired axial thickness or dimension. The plate 10 is preferably of polygonal shape. The plate is here illustrated as having seven sides or edges equiangularly disposed and of equal length. The seven-sided plate is illustrative only, and it will be understood that the plate may have any selected number of edges. In general it may be said that the lengths of the edges of the plates will preferably be substantially the same in all figures or shapes; that is, if the plate 10 is an octagon, then each individual edge thereof will be of the same length as the edge of a hexagonal plate. Thus the greater the number of sides, the greater will be the radial dimension of the plate, the difference being such that, after the segments 16 have been worn to a point such that the peripheral speed thereof is reduced below desired limits, the segments can be remounted upon a larger plate for further use. The hooks 12 are formed integrally with the center plate 10 and preferably are positioned in equiangularly and equispaced relation, being formed similarly and each being positioned at an intermediate portion of an edge of the plate. The hooks are preferably so formed that the adjacent peripheral edge plane of the plate extends tangent to the outermost curved portion of the hook.

The individual segments 16 are preferably formed from a plurality of cloth discs 20, as best seen in Fig. 3, which cloth discs are superimposed, one upon another, concentrically and are stitched together adjacent their center, as at 22, best seen in Fig. 4. The cloth discs may be of the same size or of slightly different sizes or diameters, and the cloth will preferably constitute woven cotton sheeting of the type commonly used in the art for the purpose of making buffing wheels. If desired, a small central layer 24 of canvas, burlap or other material, somewhat stiffer than the sheets 12, may be secured to the center thereof, as by stitching 22. The burlap preferably bears against an elongated rigid plate 26 which may be formed of metal, plastic or the like. The length of the plate 26 is preferably greater than the length of the hook members 12 and shorter than the length of the straight edge portions of the plate 10. The plate 26 preferably has a continuous substantially perpendicularly bent peripheral flange 28 formed integrally therewith. The plate unit 26, 28 forms shoulders around which the sheet material 20, 24 of the individual buff sections may be draped to form a skirt portion, as illustrated in section in Figs. 1 and 2.

A rigid plate 30 of substantially the same dimensions as the plate 26 engages the buff section at the surface thereof opposite the plate 26. The two plates 26 and 30 have registering holes formed therein, and holes in the fabric sheets 20, 24 likewise register therewith so as to receive eye members, as best seen in Fig. 4, which eye members preferably include an elongated portion 32, a pair of transverse portions 34 which pass through the apertures in said plates and fabric, and inwardly bent end portions 36 which are positioned within the confines of the flanges 28 of the plate 26. The eye member is formed of wire or other material which will retain its shape

and withstand substantial stresses in the nature of centrifugal force applied to the buffering segments in use. The portion 32 of the eye is preferably spaced from the plate 30 a distance sufficient to permit the hook 12 to be received between said parts with a snug fit which will permit manual hooking and unhooking of the parts.

It will be observed that by reason of the elongated character of the member 26, 28, the skirt segments are of elongated cross-sectional form, as best illustrated in Figs. 1 and 2. When these skirt-like segments are attached to the center plate 10 by means of the hook and eye arrangement described, the long transverse dimension of each segment will lie substantially parallel to the center member 10. Consequently, the dimensions or proportions of the device will be of the order illustrated in Fig. 2, the unit being narrow compared to its diameter, and each of the segments lying in substantially a common plane. It will be understood that the fabric discs or members 20 are formed of a dimension which substantially exceeds the length of each edge portion of the center plate 10 so that the adjacent segments abut along radial portions 38. The abutment of these segment portions further assists in bunching the skirted fabric so that the peripheral edges of the sheets of the fabric 20 which make up the member are compactly arranged.

The radial abutting portions of adjacent segments may be stitched together, as illustrated at 40, thus forming a continuous belt which is pre-assembled from the various segments. This arrangement eliminates the necessity of handling the individual segments in applying the fabric peripheral portion to the center plate 10 and removing the same from said center plate. The stitching 40, as best illustrated in Figs. 2 and 3, lies substantially in alignment with the eye member 32, 34, 36 and constitutes at each occurrence thereof a radially reinforced or stiffened portion. However, the belt may be formed by circular lines of stitching adjacent to the eye member. It will be apparent that the major portions of the fabric sheets 20 which make up the skirted fabric segment are free from one another and assume individual folded shapes. This stitching, and particularly radial stitching 40, concentrates compactly the fabric segments at selected portions thereof to increase the rigidity, strength and firmness of the buffing wheel as a unit. The radial stitches 40 do not interfere with or rigidify the portions of the skirt between said radial portions 38, and the individual layers of fabric are free to assume individual folded form with the folds extending radially of the wheel and being arranged differently in each sheet in the relation or arrangement produced by the action of centrifugal force. This arrangement commonly is such that a myriad of radial channels or passages are formed in the buff segment between the individual layers of fabric thereof, the same being substantially uniformly distributed throughout the body of the buff. These radial channels or passages provide means for receiving and retaining the buffering material which is applied to the buffing wheel in use and also to assist in cooling of the buffering segments.

It will be observed in Fig. 2 at the lower portion thereof that the segments, when folded around the plate portion 26, 28, have located therein a cavity 42 between the peripheral edge of the segment and the plate 26. This cavity will

be of a length equal to the length of the plate 26 adjacent to the plate. This cavity 42 constitutes a ventilating and insulating cavity within each segment. The fabric sheets possess porosity so air may pass therethrough. Consequently, by virtue of the central location of the cavity 42 and the arrangement of myriad radial channels between the individual sheets or laminations making up the segment, air circulation is permitted throughout the body of the segment. This air circulation or "breathing" of the segments dissipates excessive heat generated during the buffing operation and reduces to a minimum the possibility that the article being buffed, such as a plated metal part, will be damaged because of excessive heat.

The preformed belt, formed by stitching together individual segments, is easy to handle and greatly reduces the time required to mount the peripheral segments upon each plate 10 or dismount or disconnect said segments from said plate. Each segment is positioned or stabilized by the adjacent segments, and the different segments cooperate, one with another, to hold the belt unit in proper position substantially within the plane of the center plate. This is quite important in a buff of this character because it will be apparent that, if a single buff as illustrated in Figs. 1 and 2 is positioned vertically, that is, with its axis horizontal, the segments positioned uppermost, if independent of one another and held in place solely by frictional engagement with adjacent segments, are unbalanced and unstable. Thus, the hooked connection and support of each upper segment upon the center plate is positioned below its center of gravity. The increased stability of the unit wherein the segments are stitched together greatly reduces the amount of time required to assemble and make up a full buffing wheel from a plurality of sections of the character illustrated in Figs. 1 and 8.

The stability of the mounting of the segments 16 upon the center plate 10 can be increased by constructing the center plate 10 in a manner illustrated in Figs. 5 to 8, inclusive. In this construction the center plate 10 has a plurality of lateral offsets 44 formed in the marginal portion thereof in equispaced and equiangular relation. Each offset 44 is preferably located centrally with respect to one of the flat edge portions thereof, as illustrated in Fig. 5. The hook portions 12' are formed integrally with and project centrally from the outer edge of the offset 44, as illustrated in Fig. 5. As shown in Figs. 6 and 7 the offsets 44 extend in a plane parallel to the plane of the metal plate 10 and are offset in a direction opposite to the direction in which the terminal or tongue portion 13 of the hook 12' extends.

Each offset 44, as illustrated in Fig. 5, is of such a dimension or size that it exceeds the size of the adjacent hook 12', extending beyond the sides and the free inner edge of the tongue 13 of said hook by a dimension greater than the thickness of the stock from which the eye members 32-38 of the different segments are formed. The offset portions 44 are slotted at 46 at opposite sides of the hooks 12' so that the hook may be bent in such a fashion that its outermost surface will lie substantially in a plane common to the plane of the adjacent edge of the polygonal plate, as best seen in Figs. 5, 6 and 7.

Observe in Fig. 6 that the eye portion 32 of the segment 16 lies substantially in a common plane with the disc 48. This construction results in a balance of the buff segments when assembled

with respect to the plane of the segments, it being apparent that the centrifugal force, exerted by the segments 16 upon rotation, is exerted in the plane of the disc 48. The provision of the offsets 44 has the additional function and advantage of providing greater stability of the buff segments at the point of contact thereof with the disc 48. Observe in this connection that in the construction illustrated in Figs. 5 and 6, the plate 39 illustrated in Fig. 4 has been omitted from the buff segments, and the fabric thereof bears directly against the edge of the plate. Inasmuch as the offset 44 has the effect of widening the edge of the plate, it increases the stability of the segment and reduces the likelihood that it will tilt out of the plane of the plate when connected to the plate by the hook and eye construction. The fact that the edge of this construction is the equivalent of a wider plate, or produces the equivalent of a wider point of contact between the plate and the buff segment, is illustrated in Fig. 8. It will be apparent from Fig. 8 that the points of contact between the buff segments and the edge are laterally spaced at different positions along the length of the contact or abutment of the parts, thus producing the stability above mentioned. This stability is of particular importance in cases where the segments retain their individual character, that is, in cases where the segments are not stitched together.

In the assembly of each individual section or portion of the buff, and before the different buff sections are mounted upon their common arbor, it is desirable to provide means to prevent disconnection of the segments and their connecting eyes from the hooks of the center plate. Novel means for this purpose are illustrated in Figs. 5, 6 and 7, the same constituting a disc 48 formed of sheet material tending normally to retain its shape, but having a certain degree of flexibility. I have found that a disc which is well suited for this purpose may be formed from cardboard or chipboard. Other materials, such as plastic sheet material, metal sheet material or the like, may be employed, if desired.

The disc 48 has a center opening 50 adapted to register with the aperture 18 and to fit around the arbor (not shown) of a buffing machine. The size or diameter of the disc 48 is less than the diameter of the plate 10 and is preferably slightly greater than the spacing of the inner edges of the lips 13 from the center of the plate 10. Consequently, when the disc 48 lies flat against the plate 10, it will underlie the hook tongues 13 at its margin, as illustrated in Fig. 6, thus obstructing or closing the mouth of the hook to prevent, or at least retard, the passage of the eye member 32 through the mouth of the hook. The disc 48 preferably is severed along a radial line at 52. This severing of the disc permits the flexing thereof to the position illustrated in dotted lines in Fig. 5, which brings the outer edge of one end portion of said disc to a radially inwardly spaced position clear of the inner end of the lip of the adjacent hook, as illustrated in Fig. 7, thus facilitating the insertion and removal of the disc 48 relative to the plate 10. As shown in Fig. 7, the inward deflection of the end of the member 48 is entailed by reshaping the same to substantially conical form, which can easily be done in the case of a cardboard or paper disc. Thus it will be apparent that, when the disc 48 is to be inserted, it may be so manipulated that the edge portions circumferentially are suc-

cessively inserted under the disc lips, which, of course, is easily accomplished with respect to one half of the disc, and then, by twisting the disc slightly, the remaining portions of the disc can be inserted under the remaining hooks and thereupon the disc can be released and restored to its normal flat condition. In this case it will lie flat against the plate 10 and will underlie and engage the inner faces of the lips 13 of the hooks. The size of the disc will preferably be such that while it may have a certain free play or clearance, nevertheless that free play or clearance will not be sufficient to permit unintentional release thereof from the plate.

The construction of buff segments, and particularly of the means for mounting the same, may be substantially simplified, as illustrated in Figs. 9, 10 and 11. In this construction a single metal anchor member may be assembled with the fabric buff member being applied thereto easily and quickly and without substantial processing as is required to effect the assembly illustrated in Fig. 4. For this purpose a metal plate or member 54 may be formed and applied as a unit to the fabric disc. Such plate preferably has an elongated shoulder portion 56 of the length required to define the desired length of the inner end of the segment to abut against an edge of the disc 10. The elongated shoulder portion 56 is characterized by inner curved edges 58 around which the cloth may fold at the ends of the plate. A projection 60 is formed at the center of the member 54 at one side thereof, the same preferably having outwardly converging edge portions 62 at its opposite ends extending for a portion only of the width of the projection 60, and inwardly converging edge portions 64. The portions 62 and 64 define shoulders 63 at their junctions. At their inner ends the edge portions 64 merge at rounded or curved portions 66 with the inner edge of the shoulder portions 56. An elongated slot 68 is formed in the projection 60 with its inner edge preferably located slightly inwardly spaced relative to shoulders 63, and with its outer edge located outwardly of said shoulders 63.

In the fabrication of the segment the individual fabric discs 20', as best seen in Fig. 10, are slotted at 70 at their center, said slot being of a length equal to or slightly greater than the reduced neck of the member 54, that is, the dimension of said member between the opposed curved edge surfaces 66 thereof. The length of said slot is slightly less than the spacing between the shoulders 63. The various layers of the fabric are stitched together at 72 around the slot 70 and preferably one or more reinforcing layers 74 of burlap, canvas or the like, are stitched at the center of each buffering segment, being provided with a slot registering with the slot 70. In the assembly of the buff segment it is necessary only to force the slot 70 over the shoulders 63 so that the ends thereof bear against and are urged inwardly by the edges 64, with the inner surface of the buff segment, and especially the reinforcing portion 74, bearing flat against the shoulder portion 56. The parts are preferably so proportioned that the inner edge of the slot 68 will be substantially flush with the outer buff fold or bend, or that the slot will be partially spanned by said fabric. This will insure that, when the slot 68 receives the hook 12 of the plate 10, the fabric will be caused to bear against the adjacent edge of the plate 10.

It will be observed that this construction sim-

plifies the assembly of each complete buffering segment, reduces labor and costs, holds the segment in the desired shape, that is, permits the skirt to be formed with the desired drape around the curved edges 58 of the shoulder portions 56, and, in general, offers substantial advantages in fabrication.

One of the difficulties of a skirted type of buffering segment of the character described is that the folding of the skirt to the elongated form shown causes a bunching of the fabric at the ends, as illustrated in Fig. 12, with the result that the end portions thereof are more solid than the center portion. For the purpose of improving the construction of the buff segments and rendering their consistency more uniform, it is desirable to use fillers in the nature of cloth inserts. Such cloth inserts may be applied in different ways. Referring to the construction illustrated in Figs. 9 and 10, the elongated portion 56 of the member 54 may be provided with a slot 76 parallel to the slot 68 and preferably of a dimension approximately equal to the longitudinal dimension of the projection 60. A generally rectangular elongated folded cloth member 78 may be passed through the slot 76, as illustrated in Fig. 10, and may be stitched at 80 to anchor it in place. The parts are of such dimension that the insert 78 will extend to the periphery of the fabric buff segment. The number of individual laminations or thicknesses of the fabric which make up the member 78 will preferably be sufficient to impart at the center of the buff segment the same solidity and firmness which that segment possesses at its ends. The virtue of this construction, in addition to making the unit of uniform solidity and rigidity, is this: that there shall be presented a substantially equal number of fabric edges uniformly at all points around the circumference so that the device will not be characterized by soft spots alternating between firm or rigid spots.

A slightly altered construction for accomplishing this purpose is illustrated in Fig. 11, wherein inserts 82 of multiple thicknesses of fabric are applied to the fabric discs 20 laterally spaced from the slot 70 and extending to the edges thereof, said inserts 82 being stitched or secured to the fabric discs 20, as shown in Fig. 11. Inasmuch as the stitches in this instance are subjected only to force resulting from the rotation of the weight of the inserts 82, the stitching 84 will be sufficient to withstand the stresses involved. The Fig. 11 construction, therefore, performs the same results as the Fig. 10 construction, differing therefrom only with respect to the manner of securing of the insert, the form in Fig. 11 being characterized by avoidance of necessity of stitching after the buff segment or any part thereof has been applied to the metal anchor unit 54.

In all of the constructions of buff wheel segments illustrated herein, including constructions wherein said segments are secured together in the form of a belt and those in which segments retain their individual character, it is desirable to preform the fabric unit. The limpness and flexibility of the buffs which causes them to assume different shapes and folds upon different successive operations until the buff has been broken in, which commonly requires as long as an hour and a half, slow down production time. When it is considered that the average fabric buff will last only a few days, it is apparent that the requirement of an hour and a half "break in"

time makes it quite costly. To avoid this and also to impart other desirable properties to the buff segment, I have found that it is desirable to soak the fabric buff, after it is assembled, in a material of thin paste or liquid state which will quickly penetrate the cloth. I propose to use a laundry filler or starch mixed with water for this purpose. A number of materials are suited for this purpose. Among such materials are the filler used in domestic laundries to stiffen fabrics, library paste, corn starch, a mixture of wheat flour and gum arabic, sago flour or other starches mixed with water, and rye flour mixed with gum arabic. Any other material may be used which will tend to stiffen the fabric without creating any tendency to stick to the metal being buffed or to increase the heat of friction generated at the metal by the buffering operation.

Individual buff segments are preferably pre-shaped by mounting them upon a center plate corresponding to the center plate 10. The segments may be soaked either before or after they are mounted on this center. After soaking thereof, the excess filler or liquid material is removed from the segments to the greatest extent possible by squeezing the same. After assembly, soaking and removal of excess liquid, the unit is mounted upon a rotatable center arbor, such as a lathe spindle or machine mandrel, and is rotated at a speed sufficiently high to subject the individual segments to centrifugal force. This rotation is continued until the segments are fully or at least partially dry, that is, until the segments are dry enough to hold or retain the radially folded skirt shape of the different laminations or layers thereof.

I have found that the segments, when processed in this manner, are shaped in their desired skirt form in a manner to distribute the edges uniformly, that is, to provide the folds of each individual thickness of cloth uniformly distributed around the periphery thereof. This provides myriad radial channels within the buff segments, and is important for various reasons. Among these reasons are that the cool operation of the wheel is assured, the buffering contact with the work piece is uniform so that there is no tendency to produce streaks, and channels are provided which facilitate the reception and retention of the buffering material. Another important advantage of the construction is that it stiffens the buff unit when dry so there is no necessity to incorporate a stiff lamination, such as the laminations 24 of Fig. 4 and 74 of Fig. 10, in the buffering segment.

Various other advantages are possessed by a device shaped of this character, among which are the fact that the centrifugal shaping of the skirt-like buff segment tends to distort the weave of the cloth at all laminations and to prevent raveling. It has been observed that the centrifugal shaping causes each layer to assume an individual shape different from the others. This presents the warp and woof threads of each individual layer at a slightly different angle to the radius of the buffering wheel compared to the others. Those layers which are so positioned that rapid raveling would occur normally at a given point thereof, are protected by the adjacent layers against such rapid raveling, and the rate of raveling of the whole unit is materially reduced as compared to the rate of raveling in other constructions. Since raveling is definitely associated with wear, it will be apparent that the less the ravel, the slower the rate of wear.

Still another advantage is that a buffering wheel made up of segments which have been saturated in this manner may be trimmed to circular shape after assembly by the use of a rotary edge cutter. 5 This is made possible by reason of the firmness and stiffness of the buff segments which will permit the proper shaping by a cutting tool, with the assurance that when the wheel is stopped, the various folds of the segment will remain in the same position they occupied while rotating, so that the peripheral surface of the buff will remain constant.

While the use of a starch or other filler is preferred, it is not necessary. Most fabrics contain 15 a certain amount of filler added thereto during manufacture. Consequently, if the cloth segments are merely wetted and then spun, as described above, the layers of the cloth will assume and hold their shape, as above described, and will permit trimming, with the buff segments tending to maintain, when stationary and after being trimmed, the same folded shape as the same maintained while spun. While this process offers advantages over the use of a buff segment 25 not so treated, insofar as reduction of "break in" time, etc., is concerned, I prefer the use of starch or other material, as described above, because of the greater stiffness and rigidity secured, and the improvement of the buff segment in other respects.

While the preferred embodiments of the invention have been illustrated and described herein, it will be understood that changes in the construction may be made within the scope of the 35 appended claims without departing from the spirit of the invention.

I claim:

1. A buffering element adapted for hooked connection to a rigid center mount, comprising a pile 40 of fabric sheets secured together centrally thereof to define a unit, said unit having an elongated central aperture therein, and a metal plate having a portion extending through said aperture and an elongated portion engaging said unit at opposite ends of said aperture, said first named plate portion having an elongated slot therein adapted to receive a hook member said elongated plate portion having a slot therein, and a multiple thickness fabric insert extending through 50 said last named slot.
2. A buffering member adapted for detachable connection with a rigid center mount, comprising a fabric unit formed of a plurality of superimposed layers of cloth, an attachment member 45 secured to the central portion of said unit, said unit being folded to skirt form, and a fabric insert secured within said skirt and cooperating therewith to render said skirt unit of substantially uniform thickness throughout.
3. A buffering member adapted for detachable connection with a rigid center mount, comprising a fabric unit formed of a plurality of superimposed layers of cloth, an attachment member secured to the central portion of said unit and including an elongated shoulder-defining portion, said unit being folded to flat skirt form around 60 said shoulder-defining portion, and a fabric insert secured within said skirt, whereby said fabric unit is of substantially uniform thickness throughout.
4. A buffering member as defined in claim 2, wherein said fabric insert is stitched to said fabric unit.
5. A buffering element adapted for hooked connection to a rigid center mount, comprising a pile 75

of fabric sheets secured together centrally thereof to define a unit, said unit having an elongated central aperture therein, a metal plate having a portion extending through said aperture and an elongated portion engaging said unit at opposite ends of said aperture, said first named plate portion having an elongated slot therein adapted to receive a hook member, said elongated plate portion having an aperture formed therein, and a multiple thickness fabric insert extending through said aperture at its center and folded upon itself, portions of said insert being secured together adjacent said plate portion.

JOHN F. LESLIE.
